MAURICE L. NOVACK, OF MINNEAPOLIS, MINNESOTA

FINGER-RING CONSTRUCTION

Application filed April 28, 1930. Serial No. 447,819.

This invention relates to finger ring constructions and the primary object is to provide a combination ring wherein two rings such as a wedding ring and an engagement ring, while separate and separable units, are so formed that they will interlock, one with the other, in substantially a single unit, when worn together upon the finger. More particularly the object is to provide a pair of 10 interlocking ring units one of which consists of a single band while the other consists of two bands which are connected by tie pieces but are sufficiently spaced apart to snugly receive the single band ring. These 15 and more specific objects will be disclosed in the course of the following specification, reference being had to the accompanying drawing, wherein:

Fig. 1 is a perspective view of a combination ring embodying my invention, the setting being removed from the crown portion that normally secures the same.

Fig. 2 is a sectional elevation of the double band unit with the single band in place 25 therein.

Fig. 3 is a sectional elevation similar to Fig. 2, but showing the two ring units as separated from each other.

Fig. 4 is a perspective view of a modified 30 form of ring, in which the two ring units are also separated for purpose of illustration.

Referring to the drawing more particularly and by reference characters, A designates 35 an ordinary band ring, such as a wedding ring. B designates generally the second ring, such as an engagement ring, and it is made up of two bands, 5 and 6, that are made integral or at least rigid with the crown or 40 so called basket portion 7 that is employed to mount the stone or other setting (not shown). Thus the bands 5 and 6 are not only rigid with respect to the portion 7 but also with respect to each other, and they are 45 parallel and spaced sufficiently apart so that

they will snugly receive the ring A between them when the latter is inserted upwardly as indicated in Fig. 3. In addition to the connecting section 7 the bands 5 and 6 are further connected by a pair of small connected links 8 and 9, that may be of any size or shape but are here shown as heart shaped by reason of the sentimental association with engagement and wedding rings. These links are rigidly secured to the spaced bands 5 and 6 by soldering or fusing, and are preferably disposed slightly below the transverse diameter of the ring thus bringing them slightly closer together than if they were diametrically opposed. The purpose of this arrangement is to slightly restrict the diametrical passageway for the reception of the ring A, so that the latter will slip into place with slight frictional contact, whereby it will not drop out of place when the device is removed from the finger. While the device is on the finger there is of course no danger of the units becoming separated.

In the modified form of the device, as shown in Fig. 4, the same inventive thought 70 applies, but instead of the engagement ring receiving the wedding ring, the order is reversed, thus the engagement ring 10, having a setting 11, is fitted into the wedding ring bands 12 and 13, which are connected by 75 links 14, 15, and 16.

It is understood that suitable modifications may be made in the structure as disclosed, provided such modifications come within the spirit and scope of the appended 80 claim.

Having now therefore fully illustrated and described my invention what I claim to be new and desire to protect by Letters Patent is:

A finger ring comprising a pair of spaced band members formed integrally with a crown portion and adapted to receive a second ring of the same internal and external cross diameters, between the band members, 85 90

cross pieces connecting adjacent peripheral points of the band members at opposite sides of the ring, said cross pieces both being arranged below the cross diameter extending horizontally under the crown portion where by they will be disposed to exert slight frictional retaining contact against the outer periphery of the second ring as the latter is moved into place toward the crown portion and between the band members.

10 Signed at Minneapolis, Minnesota, this 25 day of April, 1930.

MAURICE L. NOVACK.
